UNITED STATES PATENT OFFICE

110,163

DESIGN FOR A SHOE

Jerome Edson Andrews, Andover, Mass.

Application March 30, 1938, Serial No. 76,192

Term of patent 3½ years

To all whom it may concern:

Be it known that I, J. Edson Andrews, a citizen of the United States, residing at Andover, in the county of Essex and Commonwealth of Massachusetts, have invented a new, original, and ornamental Design for a Shoe, of which the following is a specification, reference being had to the accompanying drawing, forming a part thereof, in which

Fig. 1 is a plan view of a shoe showing my new design, and

Fig. 2 is a side elevational view of the shoe, the outline of the same being shown conventionally in dot and dash lines.

The dominant feature of my design resides in a shoe tongue of elongated, tapering contour having a flat purse located entirely within the periphery of its outer surface.

I claim:

The ornamental design for a shoe substantially as shown and described.

J. EDSON ANDREWS.
